UNITED STATES PATENT OFFICE.

JAMES H. BUSELL, OF BOSTON, MASSACHUSETTS.

HEEL-BURNISHING MACHINE.

SPECIFICATION forming part of Letters Patent No. 376,066, dated January 10, 1888.

Application filed April 16, 1887. Serial No. 235,024. (No model.)

To all whom it may concern:

Be it known that I, JAMES H. BUSELL, of Boston, in the county of Suffolk and State of Massachusetts, have invented certain new and 5 useful Improvements in Heel-Burnishing Machines, of which the following, taken in connection with the accompanying drawings, is a specification.

My invention relates to the art of burnishing boot or shoe heels; and it consists, first, in a novel method of burnishing the edges of boot or shoe heels as follows, viz: Burnishing the heel-edge in sections of its height in succession--as, the central portion first, then 10 the portion next to the tread-surface, and then the portion next to the heel-seat--and the burnishing of one section overlapping the burnishing of at least one of the other sections.

It further consists in the method of burnishing the edges of boot or shoe heels, which consists in applying the central portion of the heel-edge to the action of a moving burnishing-tool and imparting to said heel a variable reciprocating motion at right angles, or nearly 15 so, to the movement of the burnishing-tool, to burnish the portion of the heel between the top lift and the heel-seat, then applying the edge of the top lift to the action of a moving burnishing-tool and rotating the heel in the 20 plane of movement of said tool, and, finally, applying the heel-seat portion of the heel to the action of a separate moving burnishing and beading tool, as will be more fully described.

It further consists in a machine having certain 25 novel features of construction, arrangement, and combination of parts, which will be readily understood by reference to the description of the drawings and to the claims, to be hereinafter given.

Figure 1 of the drawings is a side elevation of a machine illustrating my invention. Fig. 2 is an elevation of the same, viewed from a direction at right angles to Fig. 1. Fig. 3 is a side elevation of the head of the machine, drawn to an enlarged scale. Fig. 4 is a plan of said head. Fig. 5 is a central vertical section through the bearings of the reciprocating tool-carrier and portions of said carrier, the remainder of said carrier being shown in elevation with the tool removed. Fig. 6 is a partial section on line $x-x$ on Fig. 5. Fig. 7 is a horizontal section on line $y-y$ on Fig. 5, with

the reciprocating tool in position, but shown in plan. Fig. 8 is an end view of the tool-operating shaft, its crank-pin and bearing, with 55 the tool-stock and its bearings removed. Fig. 9 is a sectional elevation of the upper portion of the shoe-support. Fig. 10 is a partial plan illustrating the position of the heel when the portion above the top lift is being burnished. 60 Fig. 11 is a plan of the burnishing-tool, drawn to an enlarged scale, with the heel to be burnished represented in dotted lines in position for burnishing the edge of the top lift. Fig. 12 is a similar view with the heel represented 65 in position for burnishing its middle portion.

In the drawings, A is a column supported by the legs A' A', and provided in its base portion with bearings a a , in which is mounted the driving shaft B, having mounted thereon 70 the tight and loose pulleys C and C' and the larger pulley, C², all as shown in Figs. 1 and 2.

To the upper end of the column A is firmly secured the frame D, the upper portion of which is forked and has formed therein the 75 bearings D' and D'', in which is mounted the shaft E, having secured thereon the pulleys F and F' and the hand-wheel G. The bearings D' and D'' are lined with composition bushings fixed therein, the bushing D³ of the bearing D' 80 projecting beyond the outer end of said bearings and having adjustably secured thereon by the set-screw a' the hub H, formed in one piece with the two cylinders H' and H'', one above and the other below said hub, said cylinders serving as bearings for the vertically-reciprocating tool-carrier I, as shown in Fig. 5.

The cylinders H' and H'' are lined with composition bushings b and b, and their outer ends are closed by means of the screw-caps H³ and 90 H³, thus forming an air-chamber at each end of the tool-carrying piston I, the air in which serves as a cushion for said piston as it approaches the extreme of its stroke in one direction and as a spring to assist in moving it 95 in the other direction.

The shaft E has set in its front end the crank-pin c, upon which is mounted the rectangular block d, which in turn is fitted to a rectangular transverse slot, d', cut in the back side of 100 the tool-carrier I in such a manner that when the shaft E and the crank-pin c are revolved said block d will be moved in said slot transversely of the tool-carrier while the latter is

being moved vertically, or in the direction of its length.

Rotary motion is imparted to the shaft E by means of the belt J, leading from the pulley C² to the pulley F, the proportions of said pulleys and the speed of the driving-shaft B being such as to revolve the shaft E at a speed of about fifteen hundred revolutions per minute, and thereby impart to the burnishing-tool J' an equal number of complete reciprocations, said tool moving vertically horizontally, or at any desired angle, but in a right line.

The tool J' is provided with the shank e, which is fitted to a socket, e', formed in the tool-carrier I, and is secured therein by the set-screw e'', and the working-face of said tool has formed thereon a series of horizontal beads, e³, which serve as so many burnishing-surfaces, which act successively upon the heel-edge presented thereto at each upward and downward stroke of the tool.

The guard J² is secured to the tool J' by screws f, (shown in dotted lines in Figs. 4 and 7,) and is provided with the beading-shoulder g, extending from top to bottom thereof, as shown. The tread-guard J² is located upon the tool J' at some distance back of the extreme front part of the rounded portion of the tool J', so that in burnishing the central portion of the height of the heel may be moved transversely of the tool J' while it is being reciprocated vertically without danger of injury to the top-lift edge by its coming in contact with the tread-guard, as shown in Fig. 12.

K is a bifurcated bracket bolted to the side of the frame D in bearings K' and K², on which bracket the shaft L is mounted, upon one end of which is secured the pulley L' and upon the other end the heel-seat-burnishing tool M, provided with frusto-conical beaded surface h, the surface h' for forming a bead on the heel-seat, and the rand-guard h², all as shown in Fig. 4. A rotary motion is imparted to the shaft L and the burnishing-tool M from the shaft E through the medium of the belt N, as shown.

O is a jack-rod connected at its lower end by a ball-and-socket joint to the stand P, secured to the base of the column A, and is bent, preferably, to the form shown in Fig. 1, and has its upper end slotted or forked to receive the lever O', which is pivoted thereto at i, and provided at one side of said pivot with the pin j, to enter the hole in the last for the purpose of supporting the shoe, and upon the other side of said pivot with the weighted handle k and with the curved slot l, through which passes the pin m, set in the forked portion of the jack-rod O, said slot and pin serving to limit the vibrations of said lever O'.

A spring, Q, attached by one end to the jack-rod O and by its other end to the bent rod R, serves to press the jack-rod with the shoe thereon toward the burnishing-tools, the operator manipulating the jack and shoe to properly present all parts of the heel-edge to

the several burnishing-surfaces by taking the toe of the shoe in his right hand and the handle k in his left hand. The bent rod R is mounted in a bearing in a split box, in which it is clamped by a binding-screw, as shown in Figs. 2 and 10, so that it may be adjusted about the center of said bearing for the purpose of changing the line of draft of the spring Q to adapt it to differently-shaped burnishing-tools.

The cylinder H' is made in two parts, secured together by the bolts n n, for the purpose of enabling the tool-carrier to be placed in position in its bearings, the bushing in the cylinder H' being inserted therein after the tool-carrier is placed in position in said cylinders.

The operation of burnishing a boot or shoe heel is as follows: Power being applied to the shaft B to revolve it by means of a belt (not shown) leading from the tight pulley C on said shaft to any suitable counter-shaft or main shaft, the operator inserts the pin j in the hole 90 in the last upon which is the boot or shoe the heel of which is to be burnished, and taking the toe of the shoe in his right hand and the handle k of the lever O' in his left hand, he first presents the edge of the heel to the action of the beaded surface of the reciprocating tool J', as shown in Fig. 10, to burnish the central portion of the heel-edge, moving the jack-rod about its ball-and-socket joint and the shoe about the pin j and the lever O' about its fulcrum-pin, so as to present all parts of the heel-edge between the top-lift and a point near the heel seat successively to the action of said tool, so as to completely burnish the central and the greater portion of the height of the heel without attempting to finish the heel-seat or top-lift portion of the heel. To accomplish this in the best manner, or so as to produce the best results, the operator imparts to the shoe-heel a lateral or sidewise motion, or a motion at right angles, or nearly so, to the motion of the burnishing-tool, said lateral motion being variable at the pleasure or will of the operator, sometimes extending to the greater part of the height of the heel and at others to only a small fraction of such height. This he is enabled to do very effectually by virtue of the reaction of the spring Q, which must be so arranged and connected as to draw the heel hard against the burnishing-tool at whatever angle the heel may be presented to said tool. This will be best understood by reference to Fig. 10 of the drawings, where it will be seen that the line of draft of the spring Q is such that the heel may be moved to the right or left of the position shown a sufficient distance to cover the greater part of the height of the heel without bringing the line of draft so far outside of the burnishing-tool as to pull the heel away therefrom or injure the heel.

He then presents the edge of the top-lift to the action of the portion of the tool J next to the guard J², with the tread-surface of the heel pressed fair against the tread-guard J², manip-

ulating the lever, as above described, to present all parts of the edge of the top lift to the action of said tool, rotating the shoe and last about the pin *j* for that purpose, and then the 5 heel-seat portion of the heel is presented to the action of the rotary tool *M* to finish that portion of the heel.

By this method of burnishing a boot or shoe heel, by finishing the central portion first upon 10 the portion of the tool removed from the tread-guard and moving the heel laterally or across the line of movement of the tool and then finishing the top lift upon another portion of the same tool and then the heel-seat upon a separate 15 burnishing-tool without removing the shoe from the jack, I am enabled to produce a fine finish upon all parts of the heel-edge without jamming the top lift out of shape or cracking or injuring the finish on any part of the 20 heel after it has once been produced.

The burnishing of the last two operations overlaps the burnishing of the first operation sufficiently to insure a perfect finish of all parts of the heel. It is quite immaterial which of 25 the last two operations takes precedence in point of time; but in order to insure the best work the central portion of the heel must be burnished first, and the two extremes may then be finished in succession, either part being 30 done first, as the operator may prefer; but, as a matter of convenience, I prefer to finish the top-lift edge next after the middle portion and the heel-seat last. The end of the shaft *E* has three holes tapped therein at different 35 distances from its center, in either of which the crank-pin *c* may be screwed if it is desired to vary the stroke of the reciprocating tool-carrier. By turning the tool carrier into a horizontal position, as indicated in dotted lines in 40 Fig. 4, and inserting therein a tool adapted for the purpose, the machine may be used for burnishing the tread-surface of the shank portion of the sole.

What I claim as new, and desire to secure 45 by Letters Patent of the United States, is--

1. In combination with a jack-rod supported by a ball-and-socket or universal joint, a lever pivoted to the upper end of said rod and provided with a pin to enter the hole in the 50 last, and a stop to limit the vibrations of said lever.

2. In combination with a jack-rod supported in a socket-step, as set forth, a lever pivoted to the upper end of said jack-rod, provided at one end with a pin to enter the hole in the last and at the other end with a weighted handle, and a stop for limiting the vibrations 55 of said lever.

3. The combination, in a heel-burnishing

machine, of a universally-pivoted jack-rod, a pivoted last-supporting lever carried by said jack-rod, and two burnishing tools or surfaces for operating upon different portions of the heel-edge, so arranged relative to and in such proximity to said jack-rod that the heel of a 65 shoe carried by said jack may be presented to the action of each of said tools in succession without removing it from the jack.

4. In a machine for burnishing boot or shoe heels, the combination of the revolving shaft 70 *E*, the crank-pin *c*, the block *d*, the tool-carrier *I*, provided with the socket *e'*, the tool *J'*, having the beaded surface *e*³ and provided with the smooth-surfaced top-lift guard *J*², the cylinders *H'* and *H*², the universally-movable 75 jack-rod *O*, and the vibrating shoe-supporting lever *O'*, all arranged and adapted to operate substantially as described.

5. In a heel-burnishing machine, the combination of the revolving shaft *E*, the crank-pin 80 *c*, the block *d*, the tool-carrier *I*, provided with the socket *e'*, the bushing *D*³, and the hub *H* and cylinders *H'* and *H*², adjustably secured upon said bushing, whereby the tool-carrier may be adjusted to be reciprocated vertically, 85 horizontally, or at any desired angle.

6. In combination with the moving burnishing-tool, a jack-rod or shoe-support having a ball and-socket step located nearly under said tool and free to be moved in any direction 90 about the center of said joint, a pivoted last-supporting lever carried by said jack-rod, and a spring connected at one end to said jack-rod and at its other end to a stationary or non-moving object so located that the draft of said 95 spring shall be in a direct line through the center of the burnishing-tool, substantially as described.

7. The herein-described burnishing-tool provided with a tread-guard, in combination 100, with a burnishing-surface for acting upon the central or concave portion of the heel-edge, curved to a segment of an ellipse, the apex or extreme outward portion of said curved surface projecting outward beyond the extreme 105 outer edge of said tread-guard, as set forth, whereby the heel may be reciprocated at right angles to the motion of said tool without danger of injury to the top lift by contact with said tread-guard.

In testimony whereof I have signed my name to this specification, in the presence of two subscribing witnesses, on this 14th day of April, A. D. 1887.

JAMES H. BUSELL.
